(57) **CLAIM**

I claim the ornamental design for set of icons for a model aircraft, as shown and described.

DESCRIPTION

FIG. 1 is a rear elevation view of a model aircraft, presenting a front view of set of icons for a model aircraft;

FIG. 2 is a detail view of FIG. 1; and,

FIG. 3 is a rear, right, top perspective view of a model aircraft showing the set of icons for a model aircraft in their environment.

Structural elements depicted by broken lines have been shown for the purpose of illustrating portions of the set of icons for a model aircraft that form no part of the claimed design. The claimed design extends to a “long dash—short dash—long dash” broken line boundary, but does not include the boundary.
